STRIP SERVING APPARATUS

Russell W. Phillips, Rockville Centre, N. Y., assignor, by mesne assignments, to Nashua Gummed & Coated Paper Company, Nashua, N. H., a corporation of Massachusetts

Application April 7, 1932, Serial No. 603,777

5 Claims. (Cl. 91—14.5)

My present invention relates to apparatus for moistening, or moistening and serving or delivering strip material, such as adhesive or gummed tape and labels, particularly in connection with packaging, labeling and the like, and aims to provide simplified, inexpensive and otherwise improved means of the class referred to. As to all common subject matter, this application is a continuation in part of my co-pending applications Serial No. 451,773, filed May 12, 1930, now Patent No. 1,959,293, dated May 15, 1934, and Serial No. 526,659, filed March 31, 1931, now Patent No. 1,959,294, dated May 15, 1934. The claims of the present application are directed to the moistening means per se or novel combinations thereof with other elements in strip serving or moistening mechanism. Claims to other novel subject matter herein illustrated and disclosed, including features other than moistening, are contained in my co-pending application Serial No. 603,778, filed April 7, 1932, now Patent No. 1,958,443, dated May 15, 1934.

In the drawings, illustrating, by way of example, certain embodiments of the invention,

Fig. 1 is a plan view of a strip server in accordance with one form of the invention, it being shown supported in operative position as upon a store counter, table, wall or the like;

Fig. 2 is a side elevation of the device of Fig. 1;

Fig. 3 is a vertical longitudinal section through the device of Figs. 1 and 2;

Fig. 4 is a vertical cross-section on the line 4—4 of Fig. 3;

Fig. 5 is a longitudinal section, on a larger scale, illustrating a modified form of strip delivering and moistening means;

Fig. 6 is a view similar to Fig. 5 but showing a further modified form for the delivery end of the strip server including a moistening means;

Fig. 7 is a vertical cross-section, looking toward the right in Fig. 6, illustrating a stop means which may be employed in the device of Fig. 6;

Figs. 8 and 9 are elevations of modified forms of tape supporting rollers;

Fig. 10 is a cross-sectional detail view of adjusting means useful with the moistening mechanism of Figs. 6 and 7;

Figs. 11 to 19 illustrate different embodiments of the invention including various features which may be employed in connection with the forms of the preceding figures. In said Figs. 11 to 19,

Fig. 11 is a plan view corresponding to Fig. 1;

Fig. 12 is a side elevation of the device of Fig. 11;

Fig. 13 is a vertical section on the line 13—13 of Fig. 12;

Fig. 14 is a rear or left end elevation of the device of Figs. 11 and 12, upon a larger scale;

Fig. 15 is a plan, on the scale of Fig. 14, corresponding to the right portion of Fig. 11, but with the severing device removed to display the underlying parts;

Fig. 16 is a side elevation showing moistening means in accordance with one form of the invention;

Fig. 17 is a side elevation of portions of a modified form of moistening means also embodying the invention;

Fig. 18 is a side elevation of a brush moistener element useful in connection with any of the figures; and

Fig. 19 is a vertical cross-section on the line 19—19 of Fig. 15.

Referring first to Figs. 1 to 4, the illustrative embodiment of the invention as there shown is particularly adapted for use where the space available is limited horizontally, as for example on store counters, tables, shelves, or in other confined areas, such as the narrow aisles or inside counter spaces of certain chain stores.

Accordingly the device as a whole is constructed and arranged to have its major extent vertically, and means is desirably provided for supporting or suspending the device in such position, as upon the edge portion of a counter, shelf, table or the like, or upon a wall, or the device may be sunk into the horizontal top of a counter or the like.

As herein illustrated, the device comprises a housing or container including side walls or upright members 1 connected at their lower parts by cross pieces or flooring 2, and at their upper ends by a top wall or platform 3, providing a feed table, these parts preferably being formed of one or more pieces of sheet metal, stamped or otherwise fashioned. The side walls 1 may be cross-connected at other points, as by the front cross member 4, Fig. 3. At the rear, that is, at the left in Figs. 1 to 3, the described housing or receptacle is open or openable for the insertion and removal of the strip supply in the form of a roll S, the described parts providing a well for the latter.

Suitable means for supporting the roll S in position to be drawn upon is provided, in this instance including a roller 5 rotatably carried, as at 6, on the side walls of the housing. The strip supply or roll S rests by gravity upon this roller, and its axis is retained in a given vertical plane with respect to the supporting roller as by means of a floating spindle 7 seen in elevation 55

in Fig. 4. At points spaced the width of the container, the spindle 7 is provided with non-circular flattened or reduced portions 8 and 9 adapted to be received in vertical slots 10—10 in the respective container side walls 1. At the upper ends of these slots are the enlarged portions or eyes 11, at least equalling in diameter that of the spindle, so that the latter may be entered through the eyes and through the core 10 of the roll S, bringing the non-circular portions 8 and 9 of the spindle into the plane of the side walls 1 and in alignment with the guide slots.

The spindle desirably has a head 12 for convenience in manipulating it. Once the spindle is inserted with a roll upon it, and its reduced portions have been engaged in the slots, the spindle is held against unintentional withdrawal and is guided for vertical movement. The roll and spindle thus in effect float upon the under roller 5, while the roll S is permitted to turn readily upon the spindle. The tape or strip is preferably drawn off from the under face of the supported roll, and to the rear, as indicated at T in Fig. 2, in which case the described roll supporting and guiding means automatically affords a braking action upon the roll, preventing undesirable overrunning of the latter, by reason of the frictional resistance resulting from the weight of the roll and spindle upon the roller 5. The roll S is thus in effect self-braking. As illustrated in Fig. 2 the tape in the roll S is assumed to be wound gummed side in. Should the tape be wound gummed side out, it may be led off in the opposite direction at the bottom of the roll, that is, to the right, and reversed back around the roller 5, or it may be taken off at the top of the roll, directly to the left.

The tape or strip T is directed upwardly from the supply over a guide roll 13 journaled in the container sides, and thence forwardly over the top wall or platform 3, through a receiving and guiding throat provided by the latter and by the opposed inwardly extending longitudinal flanges, throat sides or strip members 14—14 on the housing. The throat is preferably equipped with a longitudinally extending tape arching and friction reducing means or rib-like element 14^a, which, together with the throat structure as a whole may be similar to that disclosed and claimed in my above-mentioned co-pending applications. The strip or tape is fed through the throat by the operator by placing one or more fingers upon it at the selected point on its upper face exposed between the throat sides and moving his hand along the throat toward the delivery end.

At or near the front end of the feed throat means is provided for cutting off the tape. The container top wall or platform 3 is continued forwardly beyond the throat sides 14. The container sides are extended upwardly or otherwise formed with projections or ears 15—15 carrying a cross-bar or pin 16. Hinged on the latter, as at 17, is a forwardly and downwardly extending 65 guide plate or strip depressor 18, having its front end substantially in a vertical plane with a cross slot 19 in the feed table or platform 3.

A tape severing blade or knife 20 is adapted to be moved across the path of the tape and downwardly through said slot, to sever the strip. This blade is attached as at 21 to an actuator 22 which may be generally similar to that of my said co-pending application Serial No. 526,659, being positioned for operation by a continuation of the operator's strip-feeding finger movement, in the

course of a single uninterrupted and substantially uni-planular down-bearing forward movement of the latter's fingers or hand. In the present instance the cutter actuator 22 is reinforced and guided by side flanges 23, the rear portions of which stand flatwise adjacent, and herein outside, the ears 15, and receive the cross-pin 16, whereby the actuator is rotatably supported. The actuator and blade are normally held in up position, substantially as in Figs. 2 and 3, by suitable spring means, herein including the spring 24 of general U shape, the forward yoke portion of which underlies an intermediate portion of the actuator. The two legs of the spring extend rearwardly, beneath studs 25 on the housing ears 15, and are turned about and supported on the cross pin 16 previously mentioned. The rear end of the cutter actuator 22 has a downwardly extending tail 26 adapted to abut the tops of the side strips 14 of the throat, or other adjacent stationary part, thereby to limit the upward movement of the actuator.

In advance of the cutting-off point the strip is conducted up to and across the moistening means to be described, being guided across the front end of the feed table or platform 3, between the latter and a top guide 27 which forms in effect a continuation of the feed throat. This guide may be generally similar to that disclosed and claimed in my said co-pending application, 30 being preferably in the form of a removable clip-like member having down-turned feet 28 equipped with spring detents 29 adapted to snap into openings or depressions in the housing walls.

For moistening the strip I have provided means 35 including a reservoir or tank 30 having an enclosed rear portion 31 and a somewhat higher front portion 32. The reservoir is operatively supported between the front parts of the side frames 1 and upon a cross-member 33 extending 40 between the latter, where it is removably retained as by a spring member 34 having a finger piece 35 whereby it may conveniently be depressed to release the reservoir. The front wall of the reservoir is turned over rearwardly and downwardly to form an angular lip 36, and the front edge of the top wall of the lower portion of the reservoir is extended angularly upwardly as at 37 in substantial parallelism with said lip, leaving a transverse opening between them. 50

The moistening element proper is illustrated as a wick or brush 38; see particularly Fig. 3. The brush itself may consist of a multiplicity of bristles or hairs set into a suitable anchoring composition, as indicated at 38^a. It is removably held in the clip-like lower portion 39 of the bristle-supporting plate or support 40. This latter desirably extends substantially the full length of the bristles, to support and align these practically to their extreme free ends. The brush 60 and its supporting plate 40 are received between the previously described parallel lip portions 36, 37 of the reservoir, which assist in positioning the brush moistener and in retaining it in substantially the forwardly inclined angular position 65 as illustrated. It will be noted that the rear flange or lip 37 is adapted to contact the upper side face of the group of bristles, confining and guiding them, and to a certain extent limiting the quantity of moisture which will be conducted 70 upwardly by capillary action.

The brush may further be positively located as by means of hook-like down-turned fingers 41, 42 at the front end of the bristle-support 40. The inner finger 41 is adapted to set down through an 75

appropriate opening in the front lip 36 of the reservoir, while the outer finger or fingers 42 extend down over the reservoir front wall.

It will be noted that in accordance with the described construction the reservoir, brush and brush-support may be removed bodily as a unit, or the brush element, including the brush and the bristle-supporting plate 40, may be removed while leaving the reservoir in place. Direct access to the brush may be had merely by removing the front guide 21. The latter includes the forwardly and upwardly projecting portion 27^a directly overlying the outer end of the brush and serving to confine and direct the free ends of the bristles to insure proper moistening engagement between the lower face of the tape and the brush, as the tape is passed forwardly over the latter. This front element or clip 27, 27^a thus may herein directly cooperate with and constitute an element of the feed means, the severing means, and the moistening mechanism. It partly provides the blade-guiding front wall of the cutting slot, and assists to press the moving blade into proper cutting position. If desired the fore edge of this element 27—27^a may be made to serve as a stationary knife or severing element, against which the strip may be deflected and cut or torn off, being for that purpose serrated or otherwise formed.

In some instances, and particularly where the device is intended for handling only strips of minimum width, the supporting under roll for the strip supply may be cylindrical, as illustrated in Figs. 1 to 4. In other instances, more particularly when the device is of a width adapting it to dispense strips of greater than minimum width, or in any case, the under roll may have either of the forms as illustrated in Figs. 8 and 9. In Fig. 8, for example, the peripheral surface of the roller 5^a is concaved, the roller being of greater diameter at its ends 5^b and of decreasing diameter toward its central portion. By reason of this construction tape rolls of different widths will be centered and guided automatically by the supporting roller.

In the further modified form of bearing roller shown in Fig. 9, the roller, indicated as a whole by the numeral 5^c, includes a main roller portion 5^d of a width to receive a given minimum width tape, for example, 1½" or 2". At the ends of this main roller portion are cooperating stepped portions 5^e, 5^f, 5^g, 5^h, respectively spaced to receive and center wider rolls, for example, 2½" and 3". It will be understood that rollers such as those of Figs. 8 and 9 may be employed in connection with the device of Figs. 1 to 4, with a similar self-braking action as previously referred to.

As stated, the strip server of Figs. 1 to 4 is particularly constructed and arranged for suspension, or lateral support, in a vertical position. To this end means is provided whereby the device may be so operatively positioned adjacent a vertical face of a counter, table, wall or the like, indicated at C in Figs. 1 and 4. Such means in this instance includes one or more bayonet slots 44, 45, in one or both side walls of the housing. These bayonet slots are adapted to cooperate with buttons 46 of a bracket or like device 47 to be secured as by screws to the counter C or other part upon which the device is to be hung. Said bracket is herein illustrated as of general T-shape, including a leg 48 having a lateral foot 49 at its lower end which is adapted to underlie and support the bottom of the housing when the buttons are in locked position in the respective bayo-

net slots. If more than one such slot is used at either side wall, two of the slots in a given wall preferably are arranged substantially at right angles to each other, as shown in Figs. 2 and 3, whereby the device is held against unintentional displacement both vertically and horizontally. When so arranged, as in Figs. 2 and 3, the device as a whole is readily removed from its suspended or operating position as there shown, by rocking it slightly upward at its front or right hand end, about the button in the horizontal slot 44 as a pivot. The vertical slot 45 may then be withdrawn from its button, whereupon the device may be shifted rearwardly or to the left in Figs. 2 and 3 sufficiently to free the horizontal slot 44 from its cooperating button. By supplying similar attaching means such as the described bayonet slots at both sides of the device, it may be selectively supported at either side, to deliver the tape in the desired direction.

Referring now to Fig. 5, I have there shown a modified form of moistening means and associated parts, the same being illustrated in connection with the strip server shown and described in my said co-pending application Serial No. 451,773. It will be understood, however, that the moistening means is equally applicable to various constructions of strip server, including that of Figs. 1 to 4 herein. The illustrated strip-serving device includes a base 51 and side walls, one of which is indicated at 52, these being connected by a cross strap seen in section at 53. The moistening means includes a reservoir 56 received on the base 51 between the frame sides 52 and positioned as by a rear stop 57. In conjunction therewith I have illustrated novel means for supporting a capillary-feed or brush moistener 58, in improved cooperative relation with the strip to be moistened. As in Figs. 1 to 4, the moistening element operates at a relatively small angle with the horizontal, approximately 45° as shown. Heretofore in this type of moistener, the capillary feed element or brush has stood substantially erect, with the free ends of its hairs or bristles projecting above the reservoir, approximately perpendicular to the path of the tape or at a relatively great angle with respect to it, and the bristles or hairs have been unsupported over considerable portions of their length and at their extremities. As a result they soon became objectionably deformed and inefficient. As in the moistening means of Figs. 1 to 4 previously described, the moistening element of Fig. 5 is so arranged that the moisture-conveying fibers or hairs of the brush 58 remain substantially straight, being held against objectionable flexing at their free ends or elsewhere. For this purpose the front wall 59 of the reservoir is extended inwardly and downwardly as at 59^a, at a relatively small angle with respect to the path of the tape or to the horizontal, at approximately 45° or less as shown. In substantial continuation of this inclined portion 59^a is a flat brush rest 60 in which the moistener is removably but firmly held as by the reversely extending clamp or holder 60^a. This brush support as a whole is in this instance vertically movable, being movably associated with the reservoir as by the pivot 61, and being yieldingly urged upwardly by suitable spring means illustrated as a curved spring 62 anchored at one end in the reservoir. The reservoir and brush are removable as a unit as by means of the finger piece 63.

Referring still to Fig. 5, the strip or tape T coming from the supply is passed across the

brush along a path approaching parallelism with the hairs or bristles of the latter. Cooperating with the brush is an overlying plate or guide 64, in this instance illustrated as a fixed element or guide member having an up-turned rear edge 64^a beneath which the tape is received. This plate serves to guide the tape to and across the moistener in proper moistening relation with the latter, in cooperation with the spring 62.

10 Provision may be made for adjusting the position of this plate or guide 64, for example, as illustrated in Fig. 10.

Referring to Fig. 10, the guide, plate or depressor 64^a is pivotally supported as at 65 between the side frames and has attached to it an upright post 66 which extends loosely through ears 67 on a lug 68 rotatably held in the adjacent side frame. On this post there is adjustably threaded a nut 69, lying between the ears 67. 15 By turning this nut the guide element or plate 64^a may be shifted to adjust its relation to the moistener, whereupon the plate will be held fixed in the selected position. The means of Fig. 10 is applicable to the strip serving device of Figs. 20 25 1 to 4 as well as that of Fig. 5, or in other instances where similar moistening means are employed.

In Figs. 6 and 7 I have illustrated a still further form of moistening mechanism of general use in 30 connection with strip serving devices of the class described, the device shown in said figures, for illustrative purposes, being that of my previously mentioned co-pending application Serial No. 526,659.

35 Referring to said Figs. 6 and 7, the strip server again includes a housing of which one side wall is seen at 70. The tape T is delivered through a feed throat 71 to and past a guiding device including a movable blade 72 and a pivoted operating member 73, and thence up to and across 40 the moistening means. A reservoir or tank 74 including an enclosed rear part 75 and a front portion 76, is received between the sides of the housing, where it is removably held as by a spring latch 77. The front end of this latch is 45 upturned as at 78 to form an abutment or positioning element and guide at the front of the reservoir, but may be depressed as by its knob or finger piece 79 to release the reservoir for withdrawal.

50 The moistening element proper is in the form of a wick or brush 80 set in a suitable composition to provide a butt 81. It is removably held in the clip-like lower portion 82 of the inclined bristle-supporting plate or support 83 which may be 55 generally similar to that of Figs. 1 to 4, including the positioning fingers or flanges 86 and 85 adapted to lie over and at opposite sides of the upper edge of the reservoir front wall. As in Figs. 1 to 4, the moistening unit, including the brush and its support, is bodily removable from the reservoir, or the reservoir with the contained moistener may itself be removed as a unit.

55 In the form of Figs. 6 and 7, the reservoir, containing the brush and the other parts previously mentioned, is itself bodily movable vertically, so that the moistening element or brush may be 60 yieldingly urged upwardly against the under face of the strip to be moistened. For this purpose any suitable spring means may be employed and I have herein shown one or more leaf springs 87 beneath the reservoir and preferably but not necessarily secured to it. Whether or not secured to the reservoir these springs rest on under 65 supporting means herein including a front cross

strip 88 extending between the housing side frames, and a supplemental and generally similar cross strip 89 having an upturned portion 90 which serves as a rear stop for the reservoir and, together with the flange 78 of the latch 77, 5 as a guide for its vertical movement.

In cooperation with the reservoir I preferably provide means for accurately determining the vertical position of the reservoir and its brush, and which may also serve to adjust the position 10 of the brush as the latter becomes worn, and for other purposes, such as to control the tension upon the reservoir-supporting spring means. For this purpose I have in Figs. 6 and 7 shown an adjustable stop 91 adapted to engage over 15 the top or other part of the reservoir in the manner clearly seen in Fig. 7. This stop carries a pin 92 which is vertically movable in a slot 93 in the adjacent side frame. A clamping nut 94 is threaded on the outer end of said pin. By 20 releasing the clamping nut, the stop may be adjusted so as to vary the position of the reservoir and brush as desired and to control the tension upon the spring means. If desired, similar stops may be employed at both sides of the strip server. 25 It will be noted that in addition to the novel features mentioned, the described moistening means cooperates with the associated elements in novel combination, to effect the delivery of moistened lengths of the tape material. 30

Referring now to Figs. 11 to 15, the strip serving apparatus there illustrated is a combined or convertible counter or aisle form, adapted for use either in standing position upon a counter, table or the like, or in suspended position in a store 35 aisle, upon a wall, at the edge of a counter or like locations. In respects not otherwise mentioned the construction may be substantially the same as in the preceding figures.

In said Figs. 11 to 15, the frame or housing 40 of the strip server includes the side frames or upright members 100 interconnected at their lower portions as by the cross strips 101, 102, 103, and at their intermediate and upper portions by the floor, top wall or platform 104 constituting the bottom of the tape guide channel or feed throat, and being preferably of the ribbed construction 104^a generally similar to that of the top wall or platform 3 of Figs. 1 to 4. Inwardly projecting flanges 105, generally similar to the 50 members 14, 14 of the preceding figures, serve to confine the side portions of the strip or tape and furnish a feed slot between them for feeding access to the tape.

55 At the forward end of the feed channel is a tape severing blade, cutter or knife 106 having a finger or hand-engaging portion or actuator 107 of generally similar construction as in the preceding figures. The knife and actuator are pivotally supported as by a sleeve 107^a, Fig. 15, 60 at the rear of the actuator received on a pin 108 held in ears 109 upon the respective side frames 100. A slot 110, Fig. 11, in the feed platform 104 permits the blade 106 to be depressed to sever the tape. The blade and its actuator are 65 normally elevated by a suitable spring 111 of general U-shape, having its ends turned about the knife pivot pin 108.

70 As best seen in Figs. 15 and 19, the cutter lever or actuator 107, together with the blade 106, are constructed and arranged for ready dismounting. This is effected merely by forcing out the pivot pin 108, axially, the latter being normally releasably held in assembled position by the spring 111. For that purpose one or more 75

annular grooves 112 are formed in the pin 108, disposed to receive the end or other portions of said spring, as indicated at 111^a in Fig. 19. While the pin and cutter are thus firmly held in place, the cutter may quickly be removed for sharpening, replacement, or to afford access to underlying parts.

The tape or adhesive strip supply in roll form is received in position to be drawn upon, between the side frames of the housing, as indicated at S. The roll S has a floating support upon a roller 5^c as in the previous figures, and the axis of the tape roll is confined to a given path, as the tape roll S decreases in size, by means of the slot formations 10^a in the opposite side frames. Said slot formations have enlarged portions 11^a for entrance of a spindle 7^a having a head 12^a and reduced guide portions whereby it is retained against unintentional withdrawal, as previously described.

In Fig. 12 the tape roll S is assumed to be wound with the adhesive face of the tape outside, the tape passing upwardly from the roll supply, as indicated at T, over an upper guide roll 13^a journaled on the machine frame, thence through the feed channel 104, 105, past the cutter 106 and the moistening means, to be described, for delivery as indicated by the full line T at the right in Fig. 12.

The interior of the housing or tape well desirably is closed at the rear or left end as viewed in Figs. 11 and 12. For this purpose I have illustrated a rear cover plate 113 pivotally supported on the side frames near the bottom of the latter, as at 114, and extending upwardly substantially to the guide roll 13^a. The upper end of the cover 113 may be recessed or otherwise formed as at 115, Fig. 11, for engagement of the operator's finger to open it against the closing tension of a suitable spring 116, herein supported on the cover pivot 114.

It will be observed that the tape roll supporting means, the feed channel and guides, and the tape severing means are similarly cooperatively disposed as in the preceding figures, but with the feed channel somewhat downwardly and forwardly inclined. As in the form of Figs. 1 to 10, the tape may be engaged by the operator's finger at any desired point along the channel 104, 105, and is fed out past the severing and the moistening means by forward down-bearing movement of the operator's finger or hand along an uninterrupted substantially uni-planular path, the feeding, moistening and severing operations being effected in the course of this single continuous manual operation.

In accordance with my invention the strip server of Figs. 11 to 15 is constructed and arranged for use either as a counter or table device, either upon a horizontal supporting surface, or as a suspended device as described in connection with Figs. 1 to 4. Further, when used in suspended position, as in a store aisle, it may be supported so as to face and feed in either direction. Accordingly I have provided, at each side of the strip server, suspending formations for cooperation with suspension means upon the counter, wall or other part upon which the device is to be mounted. As best seen in Fig. 12, such suspension formations, as herein illustrated, comprise a series of key-hole slots 117, 118 and 119, on each of the side frames 100. The longitudinal center lines of two of these slots, herein 118 and 119, are disposed substantially along arcs drawn from a central point 117^a at the closed end of the other

slot 117 as a center. A bracket 120 is provided for attachment, as by means of screws 121, to the counter or the like C, Fig. 11. The bracket carries laterally projecting studs 122, 123, 124 located to correspond with the positions of the key-hole slots 117, 118, 119.

In attaching the strip server the stud 122 is first entered into the larger end of the slot 117, and the strip server is then moved forwardly to bring the stud into the narrower portion of said slot 117. With the front portion of the device slightly elevated about the stud 122 as a pivot, the studs 123 and 124 may then be entered into the larger portions of their corresponding slots 118 and 119, whereupon the forward portion of the strip server may be dropped down into its operative supported position as in Fig. 12. Subsequent removal of the strip server is readily effected by a reverse procedure. Preferably, similar and correspondingly arranged key-hole slots 20 are provided in each side frame, whereby the strip server may be mounted with its left side face adjacent the bracket, to deliver tape toward the right, as in Fig. 12, or with its right side face adjacent the bracket, to deliver the tape in the opposite direction. It will be understood that the slots and studs may be interchanged, as to the element on which they are provided, and that the demountable suspension means may otherwise be widely varied in construction.

To adapt the described strip server for use as a counter type I may provide detachable base elements or supporting means, shown in assembled position in Fig. 14. Herein for the purpose I have employed, as one convenient form, a yoke-like strap or cross bar 125 having an upstanding central portion or shoulder 126 dimensioned for reception between the side frames 100, to which it may be removably secured as by means of the screws or the like 127 received in apertures 128, see Fig. 12, in the adjacent portions of the side frames. The outwardly projecting portions of this strap 125, at the two sides of the strip server, preferably carry rubber-tipped or other supporting feet 129. Any desired number of such straps and feet may be provided, disposition for two of them being indicated in Fig. 12, at the opposite ends of the device as a whole, by means of the screw apertures 128. Obviously one or more of the described detachable base elements may have the feet centrally or otherwise arranged, or the feet may be dispensed with. Also within the scope of my invention the side frames may themselves be interchangeable, some having suspension means and others provided with base elements, for use selectively in the machine as a whole.

The tape moistening means, as well as the strip supply holding means, the feed provisions and the severing means already described may be similar in Figs. 11 to 15 as in any of the preceding figures, but as illustrated in Figs. 11 to 19 the moistening means and associated parts of the tape feeding, guiding and severing means embody novel features.

The moistening means, referring first particularly to Figs. 11 to 13, includes a tank or reservoir 130 removably received between the fore portions of the side frames and upon the cross straps 102, 103 previously described. The reservoir is removably retained against unintentional forward withdrawal as by a spring detent 34^a having an operating finger piece 35^a as in the preceding figures. A stop 131 projecting downwardly from the cross piece 103 and extending through a cor-

responding aperture in the detent 34^a serves to limit the down movement of the latter. A filling lip 132 may be provided at the front of the reservoir. The side frames 100 may be recessed as at 5 130^a to afford a grip on the reservoir for inserting or removing it. As indicated at 130^b a portion of the reservoir top wall is extended angularly upwardly and forwardly, similarly as the part 37 of Figs. 1-4, and is adapted to contact transversely 10 the upper side face of the group of bristles of the brush 133 to be described, confining or compacting and guiding them, and to a certain extent limiting the quantity of moisture which will be conducted upwardly by capillary action.

15 The moistening means further includes a brush 133 illustrated separately in Fig. 18. The brush comprises a multiplicity of bristles or hairs set into a suitable anchoring composition as at 134. The brush is adapted to be disposed with its lower 20 portion in the reservoir and the free ends of its hairs or bristles projecting from it, but in the markedly forwardly inclined position, at an angle desirably substantially not greater than 45 degrees with the horizontal, as described in connection with the previous figures. In this instance 25 the brush is provided with unitary or self-contained supporting means for retaining it at the described operating angle.

As best seen in Fig. 18, this means comprises a 30 supporting strip or plate 135 formed with a clip-like lower portion 136 in which the butt 134 of the brush is removably but firmly held. The supporting plate 135 extends upwardly and forwardly along the under face of the brush for substantially its entire length and at its front end is provided with an integral or other rest or foot 137. One or more lips 138 may be provided at 35 the fore part of the described brush unit, as by turning over the upper edge of the foot 137, or 40 a portion thereof, such lip or lips being adapted to engage over the top of the front wall of the reservoir.

It will be noted that the described brush unit 45 is a self-supporting device, the base of the foot and of the clip 136 being adapted to rest on the floor of the reservoir, and always holding the brush in the desired operative position. Hence the brush cannot slip down into the reservoir, even though the operator should merely drop it 50 into the latter without taking the slight care necessary to engage the lip or lips 138 over the reservoir front wall.

Cooperating with the described brush moistener I provide means, preferably of a non-friction 55 character, for guiding the tape across the brush in proper moistening relation with it. Herein for the purpose I have shown a rotatable element, which may be bodily fixed or vertically movable. As illustrated in Figs. 11 to 15, said 60 element comprises a roller 140 rotatably mounted between ears or upward extensions 141 on the side frames 100. These ears are formed with bearing apertures or slots 142 for reception of the roller journal or bearings 143. Thus the brush-cooperative 65 roller is supported on the frame of the strip server in position for either fixed or vertically movable moistening cooperation with the brush when the latter is in operative position. Rearwardly of the roller 140 is a guide clip 144 having 70 side portions holding it resiliently in position overlying the lower portion of the feed channel, in a manner generally similar to the element 27 of Figs. 1 to 3. In the present instance the clip 75 144 is elongated to extend from a point rear-

wardly of the cutter 106, past the latter and substantially up to the moistener roller 140, so as to overlie and accurately guide the tape up to and between the latter and the brush. A slot 145, Fig. 11, is formed in the clip, in line with the 5 underlying slot 110 in the platform itself, for the down passage of the knife 106.

In a modification as illustrated in Fig. 16, the moistening roll 140^a is mounted upon the removable reservoir, as an element thereof. In this instance, referring to said Fig. 16, the reservoir side walls are formed with ears or projections 146 having apertures or slots 147 for the bearings 143^a of the roll. This construction, wherein the roll remains in operative association with the 15 reservoir, whether or not the latter is in place in the machine, has been found desirable in some instances, particularly where a plurality of reservoirs are provided in connection with any given strip server, whereby the same roll and brush 20 are continuously employed as a couple.

In a further embodiment, as illustrated in Fig. 17, the overlying tape bridge or guide member 144^a, corresponding to the element 144 of Fig. 12, is formed with a rear extension 148 including an eye 149 whereby this guide may be hingedly related to the machine frame, as by reception upon the knife pivot pin 108. In this instance a moistener-roller 140^b is supported upon the guide element, 144^a, the latter being formed 30 with up-set members or ears 150 having the bearing apertures or slots 151 for the bearings 152 of said roller 140^b. Here again the roll is supported upon the machine as a whole but may be bodily elevated to afford ready access to the 35 brush. This construction, as well as the others described, permits of substantially uninterrupted guiding of the tape fully to the moistening point. The guide element or clip 144^a carrying the roll may be resiliently held in position, similarly as 40 the element 144 of Fig. 12, with or without pivotal or other connection, if preferred.

Claims for the moistening means or couple comprising a brush and cooperating roller means, per se and in combination with strip serving 45 mechanism but irrespective of the particular form of brush support or positioning means, are contained in a copending divisional application, Serial Number 57,587, filed Jan. 4, 1936.

My invention is not limited to the particular 50 illustrative embodiments herein shown and described, its scope being set forth in the appended claims.

I claim:

1. In a strip moistening mechanism, in combination with a reservoir and its support, a brush moistener, and a brush support receivable in and bodily removable from the reservoir, said reservoir being elongated in the direction of strip movement to permit a markedly inclined positioning of the brush, and said brush support having a lower, clip portion to hold the butt of the brush, an inclined portion forwardly and upwardly extending in general direction of strip feed to lie under the brush in advance of its butt, and a rest to support the upper end of said inclined portion to present the brush in operative position. 55

2. In a strip moistening mechanism, in combination with a reservoir and its support, a brush moistener, and a brush support receivable in and bodily removable from the reservoir, said reservoir being elongated in the direction of strip movement to permit a markedly inclined positioning of the brush, and said brush support 70

- having a lower, clip portion to hold the butt of the brush, an inclined portion to lie under the brush in advance of its butt, a rest to support the upper end of said inclined portion to present the brush in operative position, and means adapted positively to interengage the brush support and reservoir to position the support longitudinally.
3. In a strip serving apparatus, a strip moistening element constructed and arranged for unitary insertion into and removal from a reservoir, said element comprising a brush and a brush support, the latter including a holder for the brush butt, an inclined backing plate and a plate-supporting foot extending downwardly from the fore part of said plate, to position the brush in forwardly and upwardly inclined position.
4. In a strip serving apparatus, a brush supporting element constructed and arranged for unitary insertion into and removal from a reservoir, said element comprising a receiver for the butt of a brush, an inclined backing plate extend-

ing forwardly and upwardly from said receiver, and an integral rest at the fore part of the plate to support the inclined portion at a given angle with the horizontal.

5. In a strip serving mechanism, in combination with a support for a strip supply, guide means providing a service path for the strip from the supply, a reservoir for liquid, a strip guiding roller rotatably supported adjacent the reservoir, a strip-moistening brush having its butt end in the reservoir and its fore end underlying said roller, and a bodily removable brush support including an inclined backing plate, a holder for the butt of the brush and a plate-supporting foot at the fore part of said plate, whereby the brush is operatively positioned at a forward and upward inclination and with its fore part in co-operative strip-moistening relation with said guiding roller.
